UNITED STATES PATENT OFFICE.

JOHN HOARE, OF CORNING, NEW YORK.

DESIGN FOR BOTTLES.

Specification forming part of Design No. **11,217**, dated June 3, 1879; application filed March 21, 1879.
[Term of patent 3½ years.]

To all whom it may concern:

Be it known that I, JOHN HOARE, of Corning, in the county of Steuben and State of New York, have invented certain new and useful Improvements in Designs for Bottles; and I do hereby declare that the following is a full, clear, and exact description of the invention, which will enable others skilled in the art to which it appertains to make and use the same, reference being had to the accompanying drawings, and to the letters of reference marked thereon, which form a part of this specification.

My invention, which is illustrated in the accompanying drawings, consists in a design for a bottle, the same being formed with straight sides, extending from the base to the neck, and with rounded corners, also extending from the base to the neck, the said sides and corners being joined by curved connections, so as to form grooves between the same, as hereinafter more fully set forth.

In the accompanying drawings, Figure 1 is a side elevation, and Fig. 2 a transverse section, of a bottle embodying my design.

A represents the bottle, having the straight

sides B B, the rounded corners C C, grooves d d, and curved connecting portions E, which connect the sides and corners and form the grooves d d.

The straight sides B, and also the rounded corners C C, extend from the base D to the neck of the bottle, as shown.

These bottles may be either plain or ornamental, after the manner in which glassware is usually cut and ornamented.

What I claim is—

The design for bottles herein shown, having the straight sides B, extending from the base to the neck, the rounded corners C, also extending from the base to the neck, and the grooves d between the sides and corners, these said sides and corners being joined by the curved connections E, all as shown and described.

In testimony that I claim the foregoing as my own I have hereto affixed my signature in presence of two witnesses.

JOHN HOARE.
